QUICK FREEZE CONTROL

Charles B. Spangenberg, Minneapolis, Minn., assignor to Minneapolis-Honeywell Regulator Company, Minneapolis, Minn., a corporation of Delaware

Application October 17, 1938, Serial No. 235,325

12 Claims.

(Cl. 62—4)

This invention relates to a control system for a refrigerating apparatus having evaporator means for cooling a space and for freezing a substance.

The prime object of this invention is to provide a control system for such a refrigerating apparatus wherein the refrigerating apparatus is normally controlled by a thermostat to maintain desired temperature conditions within the space and wherein the refrigerating apparatus may be operated independently of the thermostat until the suction pressure decreases to a predetermined low value indicating that the evaporator means has frozen the substance. When this occurs the refrigerating apparatus is then returned to the normal control by the thermostat.

Another object of this invention is to provide in combination with the above arrangement means for stopping operation of the refrigerating apparatus when the head pressure becomes excessive.

Still another object of this invention is to provide in combination with the above arrangement means for preventing starting of the refrigerating apparatus by the thermostat until the head pressure decreases to a predetermined low value and the suction pressure increases to a predetermined high value whereby the starting load on the compressor is decreased to a minimum and whereby automatic defrosting of the evaporator means during normal operation may be accomplished.

Other objects of this invention reside in the novel manner in which the above sequences of operation are obtained.

For a more thorough understanding of this invention reference is made to the accompanying drawing in which is diagrammatically disclosed the preferred form of this invention.

A fixture to be cooled may take the form of a cabinet or box designated at 10 having a storage compartment 11 and a cooling compartment 12. Located within the cooling compartment 12 is an evaporator 13 provided with a plurality of trays 14 in which a substance such as water or a confection may be placed to be frozen. A drip pan 15 collects condensate from the evaporator 13 during the defrosting cycle.

Refrigerant is supplied to and withdrawn from the evaporator 13 by means of a refrigerating apparatus generally designated at 16 which may comprise a compressor 17 operated by an electric motor 18. Compressed refrigerant flows from the compressor 17 through a high pressure line 19 into a condenser 20 and the condensed refrigerant is collected in a receiver 21. Liquid refrigerant flows from the receiver 21 through

5 a liquid line 22 into the evaporator 13 under the control of an expansion valve (not shown). Evaporated refrigerant is withdrawn from the evaporator 13 through a suction line 23 by the compressor 17. A fan 24 operated by a motor 25 may be utilized for cooling the condenser 20. Since the arrangement thus far described is conventional in the art a further description thereof is not considered necessary, it being sufficient to state that when the compressor 17 is operating a cooling action is performed by the evaporator 13.

The operation of the compressor 17 and the condenser fan 24 is controlled by a relay or starter generally designated at 27. The relay or 15 starter 27 is in turn controlled by a temperature responsive controller 28 responsive to the temperature within the fixture 10, a suction pressure responsive controller 29 responsive to the pressure on the low pressure side of the refrigerating

20 apparatus and a head pressure responsive controller 30 responsive to the pressure on the high pressure side of the refrigerating apparatus. The controllers 28, 29, and 30 acting in conjunction with the relay or starter 27 operate to start the 25 compressor 17 and the fan 24 only when the temperature within the fixture 10 increases to a predetermined high value, the pressure on the low pressure side of the refrigerating apparatus increases to a predetermined high value and the 30 pressure on the high pressure side of the refrigerating apparatus decreases to a predetermined low value and also operate to maintain the compressor 17 and the fan 24 in operation until either the temperature in the fixture 10 decreases

35 to a predetermined low value, or the pressure on the low pressure side of the refrigerating apparatus decreases to a predetermined low value or the pressure on the high pressure side of the refrigerating apparatus increases to a predetermined high value.

40 A manually operated controller generally designated at 31 is utilized for starting the compressor 17 and the fan 24 independently of the temperature responsive controller 28 to maintain the compressor 17 and fan 45 24 in operation until the pressure on the low pressure side of the refrigerating apparatus decreases to the predetermined low value or the pressure on the high pressure side of the refrigerating apparatus increases to the predetermined high value 50 for the purpose of quickly freezing the substance in the trays 14.

The relay or starter 27 may comprise a core 33 carrying an operating coil 34 and an armature 35 pivoted by a pin 36 to the core 33. The armature 35 carries in an insulated manner a

contact 37 adapted to engage a contact 38 and also carries in an insulated manner contacts 39 and 40 adapted to engage stationary contacts 41 and 42. When the operating coil 34 is energized the armature 35 is attracted to move the contacts 37, 39, and 40 into engagement with the stationary contacts 38, 41, and 42, respectively. When the operating coil 34 is deenergized, the contacts 37, 39, and 40 are moved out of engagement with their respective contacts by means of springs, gravity or other means, (not shown). The armature 35 also carries a bracket 43 the purpose of which will be pointed out more fully hereafter.

The temperature responsive controller 28 may comprise a bellows 45 charged with a volatile fluid for operating a lever 46 against the action of an adjustable tension spring 47 which in turn operates a mercury switch 48. For purposes of illustration it is assumed that the parts are so arranged that when the temperature within the fixture 10 increases to 42°, the mercury switch 48 is tilted to a closed position, and when the temperature decreases to 40°, the mercury switch 48 is tilted to an open position, as shown.

The suction pressure responsive controller 29 may comprise a bellows 50 connected by a pipe 51 to the suction pressure line 23 for operating a lever 52 against the action of an adjustable tension spring 53. The lever 52 carries in an insulated manner contacts 54 and 55 which are adapted to engage sequentially adjustable stationary contacts 56 and 57, respectively. For purposes of illustration it is assumed that when the pressure on the low pressure side of the refrigerating apparatus increases to 10 lbs., the contact 54 engages the contact 56 and when the pressure increases to 32 lbs. the contact 55 engages the contact 57. Upon a decrease in suction pressure the contact 55 first disengages the contact 57 at 32 lbs. and then the contact 54 disengages the contact 56 at 10 lbs.

The head pressure responsive controller 30 may comprise a bellows 59 connected by a pipe 60 to the high pressure line 19 for operating a lever 61 against the action of an adjustable tension spring 62. The lever 61 carries in an insulated manner contacts 63 and 64 which are adapted to engage sequentially adjustable stationary contacts 65 and 66, respectively. For purposes of illustration it is assumed that as the pressure on the high pressure side of the refrigerating apparatus decreases, the contact 63 engages the contact 65 at 190 lbs. and the contact 64 engages the contact 66 at 140 lbs. Conversely, upon an increase in head pressure the contact 64 first disengages the contact 66 at 140 lbs. and then the contact 63 disengages the contact 65 at 190 lbs.

Power is supplied to the compressor motor 18, to the fan motor 25 and to the control system by means of line wires 68 and 69 leading from some source of power (not shown).

When the temperature within the fixture 10 increases to 42° to close the mercury switch 48, the pressure on the low pressure side of the refrigerating apparatus increases to 32 lbs. to close the contacts 54, 56 and 55, 57 and the pressure on the high pressure side of the refrigerating apparatus decreases to 140 lbs. to close the contacts 63, 65 and 64, 66, a starting circuit is completed from the line wire 68 through wire 70, contacts 65 and 63, wire 71, contacts 54 and 56, wires 72 and 73, mercury switch 48, wires 74 and 75, contacts 57 and 55, wire 76, contacts 64 and 66, wires 77 and 78, operating coil 34, and wires

79 and 80 back to the other line wire 69. Completion of this circuit energizes the operating coil 34 to pull in the relay or starter 27.

Movement of the contact 40 into engagement with the contact 42 completes a circuit from the line wire 68 through wires 81 and 82, contacts 40 and 42, wire 83, compressor motor 18, and wire 84 back to the line wire 69 to operate the compressor 17. Movement of the contact 39 into engagement with the contact 41 completes a circuit from the line wire 68 through wires 81 and 85, contacts 39 and 41, wire 86, fan motor 25, and wires 87 and 80 back to the line wire 69 to operate the condenser fan 24. Accordingly when the relay or starter 27 is pulled in the compressor 17 and the fan 24 are placed in operation.

Movement of the contact 37 of the relay or starter 27 into engagement with the contact 38 completes a maintaining circuit for the operating coil 34 which is independent of the contacts 55 and 57 of the suction pressure responsive controller 29 and the contacts 64 and 66 of the head pressure responsive controller 30. This maintaining circuit may be traced from the line wire 68 through wire 70, contacts 65 and 63, wire 71, contacts 54 and 56, wires 72 and 73, mercury switch 48, wires 74, 89, and 90, contacts 37 and 38, wires 91 and 78, operating coil 34, and wires 79 and 80 back to the other line wire 69. Completion of this circuit maintains the operating coil 34 energized until either the temperature within the fixture 10 decreases to 40° to open the switch 48, or the pressure on the low pressure side of the refrigerating apparatus decreases to 10 lbs. to separate the contacts 56 and 54 or until the pressure on the high pressure side of the refrigerating apparatus increases to 190 lbs. to separate the contacts 63 and 65.

By reason of the above arrangement the compressor 17 and the fan 24 are placed in operation only when the temperature within the fixture 10 increases to 42°, the suction pressure increases to 32 lbs. and the head pressure decreases to 140 lbs. and is maintained in operation until either the temperature in the fixture 10 decreases to 40°, or the suction pressure decreases to 10 lbs. or the head pressure increases to 190 lbs. Accordingly the temperature within the fixture 10 is maintained between 40° and 42°. Since the compressor 17 cannot be started until the pressure on the low pressure side of the refrigerating apparatus increases to 32 lbs. defrosting of the exterior surface of the evaporator 13 is afforded during each cycle of operation of the refrigerating apparatus. Since it is impossible to start the compressor 17 until the head pressure decreases to 140 lbs. the starting load on the compressor motor 18 is decreased to a minimum. Since the compressor 17 can be stopped when either the suction pressure decreases to 10 lbs. or the head pressure increases to 190 lbs. safe operation of the compressor is afforded.

The manually operated control means 31 may comprise a rod 95 slidably mounted in a suitable support 96. A compression spring 98 located between the support 96 and a suitable operating knob 97 maintains a collar 99, mounted on the rod 95, against the support 96. In other words, the rod 95 is at all times urged to the right by the compression spring 98. The rod 95 carries a latch 100 which is adapted to engage the bracket 43 carried by the armature 35 of the relay or starter 27. The rod 100 carries a resilient contact 101 which is adapted to engage a contact 102 and a contact 103 which is adapted

to engage a contact 104. Contacts 101 and 103 are so arranged that they are sequentially closed upon left hand movement of the rod 95, the contact 101 engaging first the contact 102 and then the contact 103 engaging the contact 104. When the relay or starter 27 is pulled in following left hand movement of the rod 95, the bracket 43 engages the latch 100 to hold the contact 101 in engagement with the contact 102 but allowing the contact 103 to separate from the contact 104. When the bracket 43 disengages the latch 100 upon dropping out of the relay or starter, the spring 98 moves the rod 95 to the right, as shown in the drawing.

Assume now that the pressure on the high pressure side of the refrigerating apparatus is below 190 lbs. to cause the contacts 63 and 65 to engage and that the pressure on the low pressure side of the refrigerating apparatus is above 10 lbs. to cause contacts 54 and 56 to engage. If now the operator pushes the button 97 to overcome the spring 98, the contact 101 first engages the contact 102, and when the contact 103 engages the contact 104 a starting circuit for the operating coil 34 of the relay or starter 27 is completed, this starting circuit being traced from the line wire 68 through wire 70, contacts 65 and 63, wire 71, contacts 54 and 56, wires 72, 106, and 107, contacts 103 and 104, wires 108, 91, and 78, operating coil 34 and wires 79 and 80 back to the line wire 69. Completion of this circuit energizes the operating coil 34 to pull in the relay or starter 27 which causes the bracket 43 to latch behind the latch 100. After relay or starter 27 has thus been pulled in to start the compressor 17 and fan 24, the operator releases the button 97 but the latch 100 is caught by the bracket 43 to hold the contact 101 in engagement with the contact 102. A maintaining circuit is completed through the contacts 101 and 102 which may be traced from the line wire 68 through wire 70, contacts 65 and 63, wire 71, contacts 54 and 56, wires 72, 106, and 107, contacts 101 and 102, wire 90, contacts 31 and 38, wires 91 and 78, operating coil 34 and wires 79 and 80 back to the other line wire 69. Completion of this circuit maintains the operating coil 34 energized and the compressor and fan in operation until either the suction pressure decreases to 10 lbs. to separate the contacts 54 and 56 or the pressure on the high pressure side increases to 190 lbs. to separate the contacts 63 and 65. When either of these contingencies occur the relay or starter 27 drops out and the bracket 43 is released from the latch 100 whereupon the contacts 101 and 102 are separated. The control of the relay or starter 27 is therewith returned to the normal control circuits including the temperature responsive controller 28.

It is here noted that the auxiliary circuit including the contacts 103 and 104 is in parallel with the mercury switch 48 of the temperature responsive controller, the contacts 64 and 66 of the head pressure responsive controller 30 and the contacts 55 and 57 of the suction pressure responsive controller 29 so that the relay or starter 27 and hence the compressor 17 may be placed in operation independently of the temperature of the fixture 10 and the cut-in pressures on the high pressure side and the low pressure side of the refrigerating apparatus. In other words, by manual manipulation of the controller 31 the compressor 17 may be started regardless of the temperature within the enclosure 10 providing the suction pressure is not exces-

sively low and the head pressure is not excessively high. It is also here noted that the auxiliary maintaining circuit including the contacts 101 and 102 is in parallel with the mercury switch 48 of the temperature responsive controller 28 so that the compressor 17 may be maintained in operation regardless of the temperature within the fixture 10 until such time as the suction pressure decreases to 10 lbs. or the head pressure increases to 190 lbs. By reason of the auxiliary starting and maintaining circuits the compressor 17 may be maintained in continuous operation until the suction pressure decreases to the cut-out value of 10 lbs. at which time freezing of the substance in the trays 14 is assured thereby giving a very rapid freezing action. After the compressor has been stopped by the suction pressure controller 29, the manual controller 31 is rendered inoperative so that the compressor 17 is subsequently placed under the normal control including the temperature responsive controller 28.

From the above it is seen that I have provided a control arrangement for a refrigerating apparatus having evaporator means for cooling a space and for freezing a substance wherein the compressor is operated under normal control to maintain desired temperature conditions within a space and still provide intermittent defrosting of the evaporator means, wherein the compressor may be operated independently of the temperature responsive controller until the suction pressure decreases to a predetermined low value for quickly freezing the substance and wherein the compressor is returned to the normal control by the temperature responsive controller after the substance has been frozen.

Although for purposes of illustration one form of this invention has been disclosed other forms thereof may become apparent to those skilled in the art upon reference to this disclosure and therefore this invention is to be limited only by the scope of the appended claims and the prior art.

45 I claim as my invention:

1. In a refrigeration system including a refrigerating apparatus having a compressor and evaporator means for cooling a space and for freezing a substance, the combination with said apparatus of, control means responsive to the temperature of the space for normally controlling the compressor to maintain the space temperature within desired limits, control means responsive to the pressure on the low pressure side of the refrigerating apparatus for always stopping operation of the compressor when the pressure decreases to a predetermined low value, and means for operating the compressor independently of the temperature responsive control means until the compressor is stopped by the pressure responsive control means for quickly freezing the substance and thereafter returning the control of the compressor to the temperature responsive control means.

2. In a refrigeration system including a refrigerating apparatus having a compressor and evaporator means for cooling a space and for freezing a substance, the combination with said apparatus of, control means responsive to the temperature of the space for normally controlling the compressor to maintain the space temperature within desired limits, control means responsive to the pressure on the low pressure side of the refrigerating apparatus for always stopping operation of the compressor when the

pressure decreases to a predetermined low value, control means responsive to the pressure on the high pressure side of the refrigerating apparatus for always stopping operation of the compressor when the pressure increases to a predetermined high value, and means for operating the compressor independently of the temperature responsive control means until the compressor is stopped by either of the pressure responsive control means for quickly freezing the substance 10 and thereafter returning the control of the compressor to the temperature responsive control means.

3. In a refrigeration system including a refrigerating apparatus having a compressor and evaporator means for cooling a space and for freezing a substance, the combination with said apparatus of, control means responsive to the temperature of the space, control means responsive to the pressure on the low pressure side of the refrigerating apparatus, mechanism controlled by both control means to start the compressor when the space temperature increases to a predetermined high value and the pressure on the low pressure side increases to a predetermined high value and to stop the compressor when either the space temperature decreases to a predetermined low value or the pressure on the low pressure side decreases to a predetermined low value, and means operatively associated with said pressure responsive control means for also controlling said mechanism to operate the compressor independently of the temperature responsive control means until the pressure responsive control means stops the compressor for 35 quickly freezing the substance.

4. In a refrigeration system including a refrigerating apparatus having a compressor and evaporator means for cooling a space and for freezing a substance, the combination with said apparatus of, control means responsive to the temperature of the space, control means responsive to the pressure on the low pressure side of the refrigerating apparatus, mechanism controlled by both control means to start the compressor when the space temperature increases to a predetermined high value and the pressure on the low pressure side increases to a predetermined high value and to stop the compressor when either the space temperature decreases to a predetermined low value or the pressure on the low pressure side decreases to a predetermined low value, and means operatively associated with said pressure responsive control means for also controlling said mechanism to start the compressor even though the pressure and temperature have not increased to the starting values and for continuing the compressor in operation until the pressure decreases to the stopping value for quickly freezing the substance. 50

5. In a refrigeration system including a refrigerating apparatus having a compressor and evaporator means for cooling a space and for freezing a substance, the combination with said apparatus of, control means responsive to the temperature of the space, control means responsive to the pressure on the low pressure side of the refrigerating apparatus, control means responsive to the pressure on the high pressure side of the refrigerating apparatus, mechanism controlled by all of said control means to start the compressor when the space temperature increases to a predetermined high value, the pressure on the low pressure side increases to a pre- 65

5 determined high value and the pressure on the high pressure side decreases to a predetermined low value and to stop the compressor when either the space temperature decreases to a predetermined low value or the pressure on the low pressure side decreases to a predetermined low value or the pressure on the high pressure side increases to a predetermined high value, and means operatively associated with said pressure responsive control means for also controlling said mechanism to operate the compressor independently of the temperature responsive control means until either the pressure on the low pressure side decreases to the predetermined low value for quickly freezing the substance or until the pressure on the high pressure side increases to the predetermined high value.

6. In a refrigeration system including a refrigerating apparatus having an electrically operated compressor and evaporator means for cooling a space and for freezing a substance, the combination with said apparatus of, a relay for operating the compressor when energized, first switch means, means responsive to the temperature of the space for operating the first switch means, means for completing a circuit through the first switch means and the relay for operating the compressor to maintain desired temperatures within the space, second switch means, means responsive to the pressure on the low pressure side of the refrigerating apparatus for opening the second switch means when the pressure decreases to a predetermined low value, normally open switch means, means for closing the normally open switch means and for holding the normally open switch means closed as long as the relay is energized, and means for completing a circuit through the second switch means, the normally open switch means and the relay for operating the compressor independently of the first switch means until the pressure on the low pressure side decreases to the predetermined low value to freeze quickly the substance. 30

7. In a refrigeration system including a refrigerating apparatus having an electrically operated compressor and evaporator means for cooling a space and for freezing a substance, the combination with said apparatus of, a relay for operating the compressor when energized, first switch means, means responsive to the temperature of the space for operating the first switch means, second switch means, means responsive to the pressure on the low pressure side of the refrigerating apparatus for opening the second switch means when the pressure decreases to a predetermined low value, normally open switch means, means for closing the normally open switch means and for holding the normally open switch means closed as long as the relay is energized, means for completing a circuit through the first and second switch means and the relay for operating the compressor to maintain desired temperatures within the space and to stop the compressor when the pressure on the low pressure side decreases to the predetermined low value, and means for completing a circuit through the second switch means, the normally open switch means and the relay for operating the compressor independently of the first switch means until the pressure on the low pressure side decreases to the predetermined low value to freeze quickly the substance. 45

8. In a refrigeration system including a refrigerating apparatus having an electrically operated

compressor and evaporator means for cooling a space and for freezing a substance, the combination with said apparatus of, a relay for operating the compressor when energized, first switch means, means responsive to the temperature of the space for operating the first switch means, second switch means, means responsive to the pressure on the low pressure side of the refrigerating apparatus for opening the second switch means when the pressure decreases to a predetermined low value, third switch means, means responsive to the pressure on the high pressure side of the refrigerating apparatus for opening the third switch means when the pressure increases to a predetermined high value, normally 15 open switch means, means for closing the normally open switch means and for holding the normally open switch means closed as long as the relay is energized, means for completing a circuit through the first, second and third switch means and the relay for operating the compressor to maintain desired temperatures within the space and to stop the compressor when either the pressure on the low pressure side decreases to the predetermined low value or the pressure on the high pressure side increases to the predetermined high value to freeze quickly the substance.

9. In a refrigeration system including a refrigerating apparatus having an electrically operated compressor and evaporator means for cooling a space and for freezing a substance, the combination with said apparatus of, a relay including an operating coil and a load switch and maintaining switch which are closed upon energization of the operating coil, means for completing a circuit through the load switch and the electrically operated compressor for operating the compressor when the operating coil is energized, first switch means, means responsive to the temperature of the space for closing and opening the first switch means as the space temperature increases above or decreases to respectively a desired value, second and third switch means, means responsive to the pressure on the low pressure side of the refrigerating apparatus for closing the second switch means when the pressure increases to a predetermined high value and for opening the third switch means when the pressure decreases to a predetermined low value, normally open switch means, means for closing the normally open switch means and for holding the normally open switch means closed as long as the operating coil is energized, means for completing a starting circuit through the first and second switch means and the operating coil to start the compressor when the space temperature increases above the desired value and the pressure on the low pressure side increases to the predetermined high value, means for completing a maintaining circuit through the first and third switch means, the maintaining switch and the operating coil to maintain the compressor in operation until the space temperature decreases to the desired value or the pressure on the low pressure side decreases to the predetermined low value, and means for completing an auxiliary circuit through the nor-

5 mally open switch means, the third switch means and the operating coil to maintain the compressor in operation until the pressure on the low pressure side decreases to the predetermined low value to freeze quickly the substance.

10. In a refrigeration system including a refrigerating apparatus having an electrically operated compressor and evaporator means for cooling a space and for freezing a substance, the combination with said apparatus of, a relay including an operating coil and a load switch and maintaining switch which are closed upon energization of the operating coil, means for completing a circuit through the load switch and the electrically operated compressor for operating the compressor when the operating coil is energized, first switch means, means responsive to the temperature of the space for closing and opening the first switch means as the space temperature increases above or decreases to respectively a desired value, second and third switch means, means responsive to the pressure on the low pressure side of the refrigerating apparatus for closing the second switch means when the pressure increases to a predetermined high value and for opening the third switch means when the pressure decreases to a predetermined low value, fourth and fifth switch means, means for biasing the fourth and fifth switch means toward an open position, means for overcoming the biasing means to close the fourth and fifth switch means, means operated by said operating coil to hold the fifth switch means closed against the action of the biasing means as long as the operating coil is energized, means for completing a starting circuit through the first and second switch means and the operating coil to start the compressor when the space temperature increases above the desired value and the pressure on the low pressure side increases to the predetermined high value, means for completing a maintaining circuit through the first and third switch means, the maintaining switch and the operating coil to maintain the compressor in operation until the space temperature decreases to the desired value or the pressure on the low pressure side decreases to the predetermined low value, means for completing an auxiliary starting circuit through the fourth switch means and the operating coil to start the compressor independently of the first switch means, and means for completing an auxiliary maintaining circuit through the third and fifth switch means, the maintaining switch and the operating coil to maintain the compressor in operation independently of the first switch means until the pressure on the low pressure side decreases to the predetermined low value to freeze quickly the substance.

11. In a refrigeration system including a refrigerating apparatus having an electrically operated compressor and evaporator means for cooling a space and for freezing a substance, the combination with said apparatus of, a relay including an operating coil and a load switch and maintaining switch which are closed upon energization of the operating coil, means for completing a circuit through the load switch and the electrically operated compressor for operating the compressor when the operating coil is energized, first switch means, means responsive to the temperature of the space for closing and opening the first switch means as the space temperature increases above or decreases to respectively a desired value, second and third switch

means, means responsive to the pressure on the low pressure side of the refrigerating apparatus for closing the second switch means when the pressure increases to a predetermined high value and for opening the third switch means when the pressure decreases to a predetermined low value, fourth and fifth switch means, means for biasing the fourth and fifth switch means toward an open position, means for overcoming the biasing means to close the fourth and fifth switch means, means operated by said operating coil to hold the fifth switch means closed against the action of the biasing means as long as the operating coil is energized, means for completing a starting circuit through the first and second switch means and the operating coil to start the compressor when the space temperature increases above the desired value and the pressure on the low pressure side increases to the predetermined high value, means for completing a maintaining circuit through the first and third switch means, the maintaining switch and the operating coil to maintain the compressor in operation until the space temperature decreases to the desired value or the pressure on the low pressure side decreases to the predetermined low value, means for completing an auxiliary starting circuit through the third and fourth switch means and the operating coil to start the compressor independently of the first switch means, and means for completing an auxiliary maintaining circuit through the third and fifth switch means, the maintaining switch and the operating coil to maintain the compressor in operation in-

dependently of the first switch means until the pressure on the low pressure side decreases to the predetermined low value to freeze quickly the substance.

- 5 12. In a refrigeration system including a refrigerating apparatus having an electrically operated compressor and evaporator means for cooling a space and for freezing a substance, the combination with said apparatus of, a relay mechanism including an operating coil and a switch closed thereby when the operating coil is energized, a circuit for the compressor controlled by said switch, switch means operated by a temperature condition produced by said evaporator means for energizing the operating means of the relay when said temperature condition rises to a predetermined value whereby the compressor is operated to reduce said temperature condition, means including a manual operator for causing closure of said relay operated switch upon operation of the manual operator, a manual switch moved to closed position by said manual operator when so operated, mechanical connections controlled by said relay mechanism for holding said manual switch closed after release of said manual operator so long as the relay operated switch is in closed position, a circuit for the operating means of said relay controlled by said manually operated switch, and means responsive to a condition indicating that the substance has been frozen for interrupting said last named circuit.

CHARLES B. SPANGENBERG.
